UNITED STATES PATENT OFFICE.

JONAS E. TORNQUIST, OF ST. PAUL, MINNESOTA.

CAPPING MACHINE.

Application filed August 3, 1920. Serial No. 400,900.

To all whom it may concern:

Be it known that I, JONAS E. TORNQUIST, a citizen of the United States, resident of St. Paul, county of Ramsey, State of Minnesota, have invented certain new and useful Improvements in Capping Machines, of which the following is a specification.

The object of my invention is to provide a machine of simple, compact construction which will attach and clinch caps, usually of metal, previously formed and positioned, to the necks of cans and other containers, and which will perform this work rapidly and efficiently while the containers are traveling continuously through the machine.

My invention consists in certain constructions and combinations, all as hereinafter described and particularly pointed out in the claims, having reference to the accompanying drawings forming part of the specification, in which,

Figure 1 is a front view of a machine constructed according to my invention, showing the operating parts in position just before the final pressure is applied to the cap in the capping operation.

Figure 2 is a vertical section on the line 2—2 of Figure 1, showing the operating parts a step further advanced and after the capping of a can has been completed.

Figure 3 is a sectional view on the line 3—3 of Figure 2.

Figure 4 is a sectional view on the line 4—4 of Figure 1.

Figure 5 is a vertical section on the line 5—5 of Figure 1.

Figures 6 and 7 are detail views on section lines 6—6 and 7—7 of Figure 1.

Figure 8 is a sectional view on the line 8—8 of Figure 2, showing the capping and can holding members in the raised position following the position in Figure 2 and when a fresh container is moved in place for the capping operation.

Figure 9 is a horizontal section on the line 9—9 of Figure 8.

Figures 10 and 11 are detail views.

Figure 12 is a view illustrating the operation of feeding and capping the containers.

Figure 13 illustrates the mechanism for the operation of the clinching parts.

Figures 14 and 15 show a modification of the device for operating the cap clinching means,

Figures 16 and 17 illustrate the methods 55 of clinching or securing the cap to the neck of the container.

In the drawings, 10 represents the main supporting frame of the machine, which may be of any suitable construction and to which 60 is secured a table or plate 11 upon which the cans or containers to be capped are conveyed from the filling to the capping machine by means of a conveyer chain 12. This chain is provided with horizontal lugs 13, 65 between which the containers are delivered and which convey the containers continuously over the table 11 to the capping mechanism. The chain 12 may be driven from any suitable source of power, but I have 70 shown a driving shaft 14 mounted in bearings in a frame 15 adjustably secured to the main frame 10. A vertical shaft 15^a is mounted in bearings 15^b and carries a bevel gear 15^c slidably splined on the shaft 15^a 75 and in mesh with a bevel gear 15^d on the shaft 14. A sprocket 15^e secured on the vertical shaft 15^a, carries the feeding chain 12, which runs over another sprocket (not shown) near the point where the containers 80 are delivered to the feeding chain. The delivery mechanism to the chain 12 however forms no part of the present invention and is referred to only for the purpose of 85 more clearly defining the operation and function of the machine.

The main driving shaft 17 of the machine is mounted in bearings 18 on the frame 15 which is adjustably secured to the frame 10 by means of screws or studs 19 and 20 90 in slots 21 and 22. (Figures 1, 3 and 5.) A threaded rod 23, having collars 24 and an operating handle 25 is loosely mounted in a boss of the frame 10 and its threaded portion engages an internally threaded lug 26 95 upon the frame 15. By turning the handle 25, the frame 15 may be either raised or lowered for the purpose of adjusting the machine to different sizes of containers. All the operating parts except the feeding chain 100 12 are mounted upon the adjustable frame 15, and the shaft 14, from which the feeding chain 12 derives motion, is driven from the main shaft 17 by means of a driving sprocket 27 upon said shaft 17, a chain 28 105 engaging said sprocket 27 and also a sprocket 29, loosely mounted upon a stud 30 and having an integral pinion 31 meshing with

a gear 32 keyed to the shaft 14. As this shaft 14 and the stud 30 are mounted on the adjustable frame 15, their relative position is therefore not effected by the adjustment of this frame relative to the frame 10. The driving shaft 17 carries a driving pulley 33 and also a cam wheel 34 and the entire capping mechanism is operated through the medium of this cam wheel. A plate 35 slides horizontally in V-guideways 36 on the frame 15, (see Figures 2 and 5) and a plate 37 slides vertically in V-guideways 38 in the plate 35. (See Figures 8 and 9.) The horizontal movement of the plate 35 is induced by means of a crank pin 39 secured to the cam wheel 34 and engaging a connecting rod 40, pivotally connected to the plate 35 by a stud 41 (see Figures 1, 3 and 7). This stud is preferably made adjustable in a slot 42 in order to adjust the capping mechanism carried by the plate 35 to the proper position relative to the cans, as they are brought in place for the capping operation by the feeding chain 12.

The stud 41 is secured in the desired place in the slot 42 by means of a clamping nut 43 and a shoulder 44. The vertical movement of the plate 37 in the plate 35 is induced by the vertical swing of the connecting rod 40, acting through a pin 45, secured in the plate 37 and projecting into a slot 46 in the connecting rod 40. (See Figures 2 and 3.) A bearing block 47 is preferably provided on the pin 45 to reduce its wear in the slot 46 and the slot permits the pin 45 to change position in the rod 40 when the plate 35 is adjusted as above described. As the cam wheel 34 is rotated, the plate 35 is given a horizontal, reciprocating movement and the plate 37 both a horizontal and vertical reciprocating movement. The horizontal movement of the plates closely synchronizes in speed and direction with the movement of the feeding chain 12 during the period when the crank pin 39 is at the lower portion of its travel, as shown in Figure 3, and the vertical movement of the plate 37 controls and mainly effects the capping operation during this period. A cylinder or barrel 48 having slots 48^a is secured to a flange 49 of the plate 37, in which barrel is located a sleeve 50, having at its lower end a flange 51, upon which is supported a series of depending segmental clincher blocks 52. These blocks are provided with inside beveled edges 53, adapted to move under the flange 54 of the cap 55, and under the shoulder 56 of the neck A of the container B, as shown in Figure 12. The upper part of the neck A above the shoulder 56 is slightly beveled as shown particularly in Figures 16 and 17 and the cap 55 is placed loosely on the beveled surface. The blocks 52 are loosely supported on the flange 51, and are normally held in a lowered position by the sleeve 50, and separated as shown in Figure 8 by coil springs 57. In this position an inclined shoulder or cam 58 on the periphery of the blocks is positioned just below the lower edge of the barrel 48. When the barrel 48 is forced downward over the cam 58 the lower edges 53 are moved inward or towards the center of the neck of the container. When the blocks are thus moved inward their beveled inner surfaces form a conical die under the lower or free edge of the cap. A plunger 59, having a slotted head 59^a, is mounted in the sleeve 50 and its lower threaded end is provided with a hardened steel presser block 60.

A pin 61 passes through the slotted head 59^a of the plunger 59 and a toggle link 62, having an upper toggle joint connection at 63 with a toggle block 64, embraces this pin with its lower slotted end. A toggle shaft 66 keyed to the toggle block 64 passes loosely through the sleeve 50 and the lower end of a link 67 and is also keyed to a rocker arm 68. The link 67 extends upwards and is pivotally and adjustably connected to a slotted cam arm 69 by means of a shouldered stud 70 passing through the arm 69 and an eccentric 71 in the link 67.

The eccentric 71 is preferably integral with an adjusting plate 72 having a series of radially arranged holes 73, (see Figure 1) and a pin 74 in the link 67 is adapted to engage any one of these holes and lock the plate in any desired position. By removing a lock nut 75 on the stud 70 the plate 72 may be disengaged from the pin 74, and the eccentric 71 may then be turned around to effect the vertical adjustment of the capping mechanism with respect to the neck A of the container B after which the parts will be secured in the adjusted position by the pin 74 and lock nut 75. The cam arm 69 has pivotal connection to the plate 35 at 76 and a pin 77 having a collar 77^a projecting from the plate 37 into a slot 78 in the cam arm 110 (Figure 2) by which the vertical movement of the capping sleeve 50 is delayed and controlled. The uniform, vertically reciprocating motion of the plate 37 and barrel 48 is thereby converted into an irregular intermittent movement of the capping sleeve 50 and plunger 59 to effect the proper timing of the co-operating parts in the capping operation, as will hereinafter be more fully set forth. The rocking of the shaft 66 to cause the toggle action of the capping sleeve and plunger as heretofore described is effected in proper sequence of operation as follows:

Depending arms 79 and 79^a, integral with a hub 79^c (Figure 4), are pivoted at 80 to the frame 15 and the arm 79 is provided with a roller 81 and the arm 79^a with an adjusting slot 82, as shown in Figures 1 and 3. The roller 81 is held against the periphery or face of the cam wheel 34 by a ten-

sion spring 83 and a cut-away portion 84 of the face of the cam wheel, terminating in a rather abrupt shoulder 85, imparts intermittent swinging motion to the arms 79⁵ and 79^a as the cam wheel rotates. A cam arm 86 is adjustably pivoted to the arm 79^a in the slot 82 and is secured in the adjusted position by a shouldered bolt 87 and clamping nut 88 similar in construction to that shown in Figure 7. A longitudinal slot 89 having a central cam portion 90 (see Figure 13) is provided in the cam arm 86 and a pair of rollers 91, fastened to the rocker arm 68, on the toggle shaft 66, project into the slot 89. As the cam wheel 34 rotates, the weight of the arm 79, aided by the tension of the spring 83, keeps the roller 81 with considerable force against the annular face of the cam wheel, and in this position, as shown in Figures 1, 2 and 13, the toggle block 64 depresses the pin 61 and exerts a downward pressure on the plunger 59. When, however, the roller 81 passes into the cut-away or depressed portion 84 of the wheel, the cam arm 86 and toggle block 64 will assume the position shown in Figure 8, and the toggle pressure is released from the pin 61. This pressure is properly timed, by the location of the shoulder 85 on the cam wheel 34, to occur immediately after the blocks 52 are moved inward under the edge 54 of the cap 55 on the neck of the container B.

The reaction of the toggle members also exerts an upward pressure through the shaft 66 (Figures 2 and 8) on the sleeve 50, and the blocks 52 carried by said sleeve, there being sufficient looseness in the parts to permit the straightening out of the toggle members to create an upward pull on the sleeve 50, and the blocks 52, thereby causing the blocks 52 to exert an upward pressure, opposing the downward pressure of the plunger. This action tends to balance the pressures on the cap and neck of the container. At the same time the upward pressure of the blocks 52 assists in closely and firmly clamping the lower edge of the cap against the shoulder on the neck of the container (Figure 17).

The containers B, being in the present instance preferably of the form shown in Figures 5 and 13, are, as above described, conveyed from a suitable filling machine to the capping machine by the chain 12. I prefer to have the containers pass under a chute 91^a (see Figure 12) through which the caps 55 are delivered in the proper inclined position. The neck A of the container engages, with this arrangement, the lower protruding portion of the flange 54 of the lower cap, and the cap dropping in place on the neck A, is partially pressed on the container by passing under an idler wheel or roller 92^a, (Figure 12) and is carried in this posi-

tion under the capping mechanism. The caps are normally held in the chute 91^a by a suitable friction device (not shown) from which they are released when engaged by the containers. Means are preferably provided for guiding, gripping and holding the container firmly in position, while traveling with the chain 12 during the capping operation, as follows:

Referring to Figures, 1, 5, 8 and 10, converging guide plates 93 and 93^a, engaging the top of the containers, are secured to the frame 15 by means of brackets 94, and are preferably provided with an upward flaring receiving end 94^a. A depending gripper arm 95 is pivoted to the plate 37 at 96, and is connected at 95^a to a link arm 97 which in turn is connected at 98^a to a gripper arm 98, pivoted to the plate 37 at 99. The link arm 97 is connected to the gripper arms 95 and 98 so that a movement of the link arm to the right will separate the gripping arms and a movement to the left will close the arms, and these movements are effected by means of an upwardly projecting arm 101 integral with the link arm 97 and having a cam slot 102 in which is located a pin 103. This pin is connected to the plate 35. The vertical movement of the plate 37 causes the cam slot in the arm 101 to throw the link arm 97 horizontally, when the pin 103 passes the offset portion 104 in the slot 102, thus either opening or closing the gripper arms 95 and 98. I prefer to provide a cushion for the container and gripper contact, and for this purpose the pin 103 is not fastened directly to the plate 35 but to a swinging angle plate 105 pivoted to the plate 35 at 106 and normally held against the edge of the plate 35 by a coil spring 107, adjustable upon a rod 108, as to tension, by a threaded nut 109, as shown in Figures 8 and 9. When the gripper arms press against the container, the plate 105 will swing more or less on its pivot, according to any irregularities there may be in the size or forms of the containers and by depressing the spring 107 will tension the containers firmly between the grippers.

In the operation of the machine, the arrival under the capping mechanism of a container B with a cap 55 on the neck thereof, as above described, is timed to coincide with a diagonally downward movement of the plate 37, the horizontal movement of the plate 35 together with the downward vertical movement of the plate 37, giving this resultant diagonal movement to said plate 37 and the parts carried thereby. At this time, and slightly before the parts resume the position shown in Figure 1, the gripper arms 95 and 98 are in the open and elevated position shown in Figure 8, and as the plate 37 descends the grippers 95, 98, close down over the sides of the container, and, by the

clamping action of the link arm 97, the container is made to travel horizontally with the plate 37, preferably, at certain points, a little faster than the chain 12. The cap 55 has now passed under the sleeve 50 carrying the blocks 52, and as the plate 37 descends these blocks move downward and inward towards the neck of the container and under the free edge of the cap 55, (Figures 16 and 17). During the downward movement of the plate 37, as shown in Figures 2, 3 and 12, the blocks 52 are, as already stated, brought downward and inward and under the flange of the cap 55, and these blocks are held in that position by the cam arm 69 as shown in Figure 8 of the drawings. By a further downward motion of the plate 37 the barrel 48 is brought down to close the blocks 52 around the neck of the container. At this point the plunger 59 is forced down onto the cap by the toggle joint 64, which forces the cap downward, causing its free edge to ride over the conical die seat formed by the inner surfaces of the blocks 52. At the same time the straightening out of the toggle members causes the sleeve 50 to be pulled upward slightly thereby pressing the jaws or blocks 52 upward counteracting the downward pressure of the plunger, thereby balancing the pressure upon the upper and lower sides of the shoulder around the neck of the container, and at the same time aiding in closely pressing the flange of the cap into a snug and permanent position beneath the shoulder of the container. The upward pressure exerted by the jaws or blocks 52, therefore, counteracts and balances the downward pressure exerted by the plunger, while at the same time these two opposite pressures squeeze the edge of the cap and its flange so as to make a very effective seal around the neck of the container. The edge of the cap is thereby turned inward close to the neck of the container, which firmly secures or clinches the cap in place thereon, making a smooth joint between the edge of the cap and the neck of the container around which said cap is closed (see Figure 17).

As shown in Figures 1 and 8, the toggle members have again been released after the clinching of the cap is completed. On further rotation of the cam wheel 34 the plate 37, still moving horizontally, is gradually raised, first to release the clinching blocks 52 from the container while the pin 77 traverses the slot 78 in the cam arm 69. When thereafter the pin strikes the curve of the cam in the arm 69, the clinchers parts, operating in the barrel 48, will be raised away from the container, thereby permitting the container to continue its travel on the table 10. While the crank pin 39 of the cam wheel 34 completes the upper arc of its travel, another container is brought in position by the traveling chain 12 to be grasped by the gripper

arms 95 and 98 and the operation will be repeated.

In Figures 14 and 15 I have shown a modification in which I substitute the straight bar 120 for cam bar 86, and dispense with the toggle arrangement located at the upper end of the plunger 59^a. As here shown the bar 120 is substituted for the bar 86 having cam slots therein. This bar passes between the stud 61 and the shaft 66, as shown in Figures 14 and 15 of the drawing. The bar 120 is provided with the shoulders 121 so that when the bar is moved horizontally the plunger 59^a is caused to descend and the sleeve 50 to which the jaws or blocks 52 are connected is moved upward slightly, the action being similar to that obtained with the toggle joint already described. This device accomplishes the same result as the toggle joint device, but is somewhat simpler in construction, and may in some instances be preferable in use.

I do not limit myself to the use of this mechanism for the application of caps to the form of containers shown in the drawings. The containers here shown are formed of sheet metal and are particularly adapted for holding syrup, and the machine has been designed particularly for applying caps to these containers. It is obvious, however, that without any material modifications the machine may be adapted for applying caps to other forms of containers or to containers formed of other materials.

The details of the construction may be modified in many particulars without departing from my invention.

I claim as my invention:

1. The combination, with means for supporting a container to be capped, of a cap sealing mechanism comprising jaws arranged to close under a cap in position on the neck of a container, means for closing said jaws under said cap, means for forcing the edge of said cap against said jaws, and causing said edge to be turned inward, and means for simultaneously moving said jaws in a direction opposite to the line of pressure on said cap.

2. The combination, with means for supporting a container to be capped, of a cap sealing mechanism comprising jaws arranged to close under a cap in position on the neck of a container, means for closing said jaws, means for forcing said cap downward, and causing its edge to be turned inward by contact with said jaws, and means for simultaneously pressing said jaws upward and applying pressure to the under side of the neck of the container in opposition to the downward pressure applied to said cap.

3. The combination, with means for continuously feeding the containers to be capped, of a cap sealing mechanism comprising

- ing jaws arranged to close under the edge of a cap in position on the neck of a container, means for forcing said cap downward and causing its edge to be turned inward by said jaws and means for simultaneously pressing said jaws upward, said mechanism being mounted to move synchronously with the containers during the sealing operation.
10. 4. The combination, with means for continuously feeding containers to be capped, of mechanism, comprising jaws arranged to close under the edge of a cap arranged on the neck of a container, a plunger operating between said jaws and co-operating therewith to seal the cap on the container, and means for pressing said jaws upward in opposition to the pressure applied by said plunger, said mechanism being mounted to move in the direction of movement of the container during the sealing operation.
5. The combination, with means for feeding containers continuously, of means for engaging and sealing a cap, arranged on the neck of a container, said means including jaws adapted to close under the edge of the cap, and a plunger mounted to exert a pressure on the cap, thereby moving the cap downward and causing its edge to be turned inward by contact with said jaws and means for pressing said jaws upward.
6. The combination, with means for feeding containers continuously, of jaws mounted to close under the edge of a cap arranged on the neck of a container, a sleeve supporting said jaws, a plunger mounted to exert pressure on the cap, a barrel enclosing said sleeve and mounted to engage said jaws and press them inwardly and means for pressing said jaws upwardly.
7. The combination, with means for feeding containers continuously, of jaws mounted to close under the edge of a cap arranged on the neck of a container, a sleeve supporting said jaws, a barrel mounted to press said jaws inwardly, a plunger operating between said jaws to bear on the cap, means for operating said plunger and means for pressing said jaws upwardly.
50. 8. The combination, with means for feeding the articles to be capped, of reciprocating plates and means for operating the same, a cap sealing mechanism mounted to engage and seal the caps on the articles, and a toggle mechanism actuated by the movement of said plates for operating said sealing mechanism.
60. 9. The combination, with means for feeding articles to be capped, of a sealing mechanism comprising jaws closing under the edge of the cap, a plunger operating between the jaws for pressing downward on the top of the cap and thereby causing the lower edge of the cap to be turned inward, a cam arm, a cam operating said arm, a toggle shaft, toggle mechanism interposed between the shaft and plunger, and mechanism operating said toggle shaft intermittently to exert a downward pressure on the plunger.
10. The combination, with means for feeding articles to be capped, of a sealing mechanism comprising jaws for closing under the edge of a cap, a sleeve supporting said jaws, a barrel wherein said sleeve is mounted, said barrel having a vertical movement for pressing said jaws together under the flange of the cap, a plunger operating in said sleeve to exert a downward pressure on the cap, and thereby to cause its edge to be turned inward by said jaws, and mechanism for operating said sleeve and plunger to exert simultaneously an upward pressure on the sleeve and a downward pressure on the plunger.
11. The combination, with means for feeding the articles to be capped, of jaws for closing under the edge of a cap in position on the article, a sleeve supporting said jaws, a plunger operating in said sleeve, mechanism for moving said sleeve downward to position the jaws, and mechanism for depressing said plunger to exert a pressure on the cap to cause its edge to be turned inward by the jaws and for exerting pressure on the jaws in opposition to the pressure applied by the plunger.
12. The combination, with means for feeding the articles to be capped, of a capping mechanism comprising a barrel mounted for vertical movement, a sleeve enclosed by said barrel, cap closing jaws carried by said sleeve and adapted to be engaged by the downward movement of said barrel, a plunger mounted within said sleeve, mechanism for depressing said sleeve to adjust said jaws in their working position, and mechanism for operating said plunger to exert a pressure on the cap, and cause its edge to be turned inward by said jaws.
13. The combination with means for feeding the article to be capped, of a reciprocating capping member and sectoral die members mounted thereon, inwardly projecting flanges arranged upon said die members, means cooperating with said capping member to radially expand said die members and pass them over and beyond the cap, means to radially contract the die members under the edge of the seated cap to form a die, means cooperating with said capping member for thereafter forcing the cap against the die and turning the lower edge of the cap inwards towards the seat of the cap and means for pressing said die members upwardly.
14. The combination with means for feeding the article to be capped, and a reciprocating capping member, of radially swinging die members mounted on said capping member and having inwardly converging

flanges, means cooperating with the reciprocating capping member for moving said die members over and beyond the edge of a cap seated on said article and radially contracting said flanges to form a die during one stroke of said capping member, a plunger between said die members for forcing the cap against the die and turning the edge of the cap inwards, and means for expanding 10 said die members radially during the succeeding stroke of the capping member to release the die from the cap and pressing said die members upwardly.

15. The combination with means for feeding a container and seating a cap thereon, of a reciprocating member having a cylinder, mounted thereon, a sleeve working in said cylinder, radially movable sectoral die members mounted on said sleeve, a plunger operating through said sleeve between said die members, means for reciprocating said sleeve and said die members independently of the movement of said reciprocating member and cam faces upon said die members cooperating 25 with said cylinder to radially expand and contract said die members when said sleeve and die members are reciprocated independent of said cylinder.

16. The combination with means for continuously feeding the article to be capped, of a reciprocating capping member, sectoral die members mounted thereon and having inwardly projecting flanges, means cooperating with said capping member to radially expand said die members and pass them over and beyond a cap seated on said article, means for thereafter contracting the flanges of said die members under the edge of the cap to form a die, cooperating means for 35 forcing the cap against said die to turn the edge of the cap inwardly towards the seat of the cap, means for pressing said die members upwardly and means cooperating with said capping member for synchronously moving said die with said article during the capping operation.

17. The combination with means for feeding a container, of a reciprocating capping member and sectoral die members mounted thereon, inwardly converging flanges arranged upon said die members, means, cooperating with said capping member to radially expand said die members and pass their flanges over and beyond the edge of the cap, and thereafter contracting the die members to form a die, a plunger mechanism for moving the cap against the die to turn the edge of the cap inwardly means for pressing said die members upwardly, and means for moving said plunger mechanism and die synchronously with said container during the capping operation.

18. The combination with means for feeding the article to be capped, of a reciprocating member having a cylinder mounted

thereon, a sleeve working in said cylinder, radially adjustable die members mounted on said sleeve, a plunger operating through said sleeve between said die members, means for moving said plunger independent of said sleeve and means for adjusting the relative operating positions of said plunger and said sleeve and die members.

19. The combination with means for feeding the article to be capped of a reciprocating member having a cylindrical barrel mounted thereon, a sleeve working in said barrel, an arm having adjustable link connection to said sleeve and slotted cam connection to the reciprocating member, radially adjustable die members mounted on said sleeve and a plunger operating through said sleeve between said die members.

20. The combination with means for feeding the article to be capped, of a reciprocating member having a cylindrical barrel mounted thereon, a sleeve working in said barrel, radially adjustable die members mounted on said sleeve, a plunger operating through said sleeve between said die members, a link connection to said sleeve and having slotted connections to said reciprocating member and a cam arm operable from a cam wheel for moving said plunger relative to said sleeve.

21. In a capping machine the combination with a carrier continuously moving the article to be capped and a reciprocating member having a capping device mounted thereon, of clamping jaws mounted upon said member to be passed over the sides of said article during the working stroke of said member, link connections between said clamping jaws, means for closing said jaws against said article on the capping stroke of said reciprocating member and means for moving said member and said capping device synchronously with said carrier during the clamping and capping operation.

22. In a capping machine the combination with a carrier continuously moving the article to be capped and a reciprocating member having a capping device mounted thereon, of clamping jaws mounted upon said member to be passed over the sides of said article during the working stroke of said member, an arm having a cam slot controlling said jaws, a yielding member engaging said slot, whereby said jaws are caused to be clamped against said article with a yielding pressure during the capping stroke of said reciprocating member and a sliding member upon which the reciprocating member is mounted to move synchronously with said carrier.

23. In a capping machine the combination with a carrier continuously moving the article to be capped and a reciprocating member having a capping device mounted thereon, of pivoted clamping jaws mounted upon

said member to be passed over the sides of said article during the working stroke of said member, an arm pivoted to said jaws oppositely inclined guideways to engage the upper edges of said article, means for moving said arm and closing said jaws against the sides of said article during the capping stroke of the reciprocating member and a sliding member upon which the reciprocating member is mounted to move synchronously with said carrier.

24. In a capping machine, the combination with a carrier continuously moving the article to be capped, of a reciprocating member having a capping device and clamping jaws for said article mounted thereon, oppositely inclined guideways for the upper

edges of said article, means mounted upon said reciprocating member for closing said jaws against the sides of said articles during the capping stroke of the reciprocating member, a sliding member upon which the reciprocating member is mounted to move synchronously with said carrier and means for adjusting the carrier with respect to said guideways and capping device for different size articles.

In witness whereof, I have hereunto set my hand this 1st day of June, 1920.

JONAS E. TORNQUIST.

Witnesses:

W. J. FOWLE,
F. A. ELDREDGE.
